UNITED STATES PATENT OFFICE.

IRVING B. SMITH, OF PHILADELPHIA, PENNSYLVANIA, ASSIGNOR, BY MESNE ASSIGNMENTS, TO ELECTRELLE COMPANY, OF PHILADELPHIA, PENNSYLVANIA, A CORPORATION OF PENNSYLVANIA.

MECHANISM FOR PLAYING MUSICAL INSTRUMENTS.

No. 927,692.

Specification of Letters Patent.

Patented July 18, 1909.

Application filed February 17, 1906. Serial No. 301,572.

To all whom it may concern:

Be it known that I, IRVING B. SMITH, a citizen of the United States, residing at Philadelphia, in the county of Philadelphia and State of Pennsylvania, have invented 5 new and useful Improvements in Mechanism for Playing Musical Instruments, of which the following is a specification.

My invention has relation to mechanism 10 for playing musical instruments, in which the mechanism for operating the sound-producing devices of the instrument, such as the hammers of the piano, is located within the upper part of the piano casing; that is to say, in an upright or what is known as a 15 Verteigrande piano, in that part of the casing above the keyboard of the instrument; and which mechanism is designed to be controlled by perforated music-sheet mechanism 20 of any well known type, situated in any known or desired position with respect to the instrument.

The desirability, for many reasons, of having the mechanism for operating the sound-producing devices of the instrument situated 25 in that part of the piano casing referred to, is recognized in the art. When so situated the problem of getting at the strings of the piano for the purpose of tuning the instrument, or for other purpose, has arisen, and my invention has for its object, first: to so 30 arrange the mechanism for operating the sound-producing devices of the instrument (which mechanism, for brevity, will be termed "player mechanism") in the upper portion of the casing referred to that, without in any wise disorganizing such mechanism or without disconnecting it, or any element of it, from its incorporation in or with 35 the instrument, the player-mechanism may be shifted to afford ready access to the strings of the instrument, for the purposes mentioned, or for other purpose.

The invention has for a further object a 40 novel arrangement of phrasing levers combined with a phrasing or expression device, supported by the player-mechanism carrier.

The invention also has for its object the provision of means combined with the expression controlling device whereby such device may be manipulated manually at the will of the operator, or may be set in fixed, selective position to maintain any desired expression.

The invention, finally, has for its object 55 the improvement in the arrangement and manner of mounting the armatures of the magnets which control the operation of the shoes that actuate the sound-producing devices of the instrument.

In illustrating my invention, I have shown it in connection with one known type of sound-producing devices of a musical instrument situated within the upper part of the piano casing, and will briefly refer to 60 so much of such example of sound-producing devices, as will afford a clear understanding of the invention, without, however, intending to limit myself thereto.

My invention is not concerned with any 70 particular type of sound producing devices, but rather with the new arrangement of player mechanism and accessories.

Having in view the foregoing objects, my invention consists of the features hereinafter 75 described and claimed, reference being had to the accompanying drawings for illustration.

In said drawings—Figure 1 is a vertical 80 sectional view; Fig. 2 is an elevation; Fig. 3 is a perspective view; and Fig. 4 is a detail perspective view of one of the armature-hinged blocks.

In the said drawing, the reference numeral 1 designates, generally, the upper part 85 of an upright piano casing above the keyboard thereof; 2 the upper member of the string plate of the instrument, and 3 the removable front board. Within this portion of the casing, as usual, is located the sound-producing devices, such as strings 4, and the hammers 5 and co-related mechanism, known in the art as the "action," for causing the hammers to strike the strings. A portion only of such mechanism is shown, 90 and that conventionally. In the parts illustrated the reference numeral 6 designates one of the wippens of the action, which has connection 7 with one of the keys of the key-board, in the usual or well-known manner, and which operates the hammer in the usual or well known manner.

The player-mechanism to which my invention relates, is supported upon or from a carrier which is arranged to be shifted together with the elements of the player mechanism carried thereby, and without the necessity of disconnecting any of the parts

of the player mechanism, away from in front of the string-plate of the instrument to afford access to the latter for the purpose of tuning the instrument, or for introduction 5 of new strings, or for other purpose. This carrier and the player mechanism supported thereby consist of a body 8 having at its opposite ends legs 9 connected together preferably by means of set-screws 10, 10 threaded into the legs and passing through elongated slots 11 in the arm. This arrangement affords facility of adjusting the carrier in fitting it, and the elements carried thereby, to the sound-producing devices of 15 the instrument. The legs 9 are pivoted as at 12 on pivot studs projecting from plates 13 connected to the side boards of the piano casing, preferably by means of wood-screws 14, whereby the player mechanism may be 20 incorporated within the casing without damage to the latter and with a minimum of addition to the said casing. The carrier shown is capable of being shifted away from the string-plate of the instrument, as before 25 referred to, and one suitable arrangement is shown, wherein the pivotal connection of the carrier 8 to the supporting plates 13 is through the medium of the legs 9, below the longitudinal median of the carrier, whereby 30 such carrier, and the player mechanism carried thereby, may be swung downwardly away from the string-plate and in the general direction toward the keyboard as illustrated in the dotted lines, Fig. 1; with the 35 distinct advantage set forth, and which will be further referred to. The carrier is held in operative relation to the strings and the action by a suitable keeper, shown as set-screws 15 passing through the legs 9 and 40 into engagement with the plates 13. These screws may be readily removed when it is desired to shift the carrier.

The arm extends across the piano casing in front of the strings and above the action 45 of the instrument, and connected thereto is a magnet rail 16, upon which is arranged a series of electro-magnets 17 preferably arranged in pairs, each pair, together with the mechanism associated therewith, as hereinabove described, being appropriated to a given string of the instrument.

The armatures 18 of the magnets are pivoted to hinge blocks 19 one of which is shown in detail in Fig. 4. For the purpose of positioning the armatures with accuracy in proper relation to the electro-magnets, a hinge block bar 20 is provided, in the illustrated instance of the invention consisting of a ledge or shoulder connected to or formed 55 with carrier 8. This hinge block base is in such position with relation to the electro-magnets that, when the hinge blocks are fitted thereon, and connected thereto, as by means of screws 21, the armatures, when 60 hinged or pivoted to said blocks, as by means

of pivot pins 22, passing through said blocks and armatures, will be in exactly proper relation to the magnets for accurate operation therewith. Pivotaly connected to saddles 23 at the free ends of the armatures are 70 shoes 24 which, when the armatures are attracted by the magnet coils (the latter are selectively energized by mechanism controlled by note perforations in a music sheet, which mechanism and sheet may be of any known suitable type and which are not shown herein as my invention is not concerned therewith) are caused to come into engagement with a prime actuator consisting of a constantly rotating roll 25 journaled in 75 hangers 26 depending from the carrier 8. This prime actuator as shown is of conical formation, whereby its surface speed gradually increases from its smaller to its larger end. It is arranged so that its smaller end 80 co-operates with the shoes that actuate the sound-producing devices appropriated to the bass notes of the instrument, and with its larger end for co-operation with the shoes appropriated to the sound-producing devices of the treble notes. The purpose of 85 this formation is to normally cause the hammers to strike the strings with progressively increased force from the lowest bass to the highest treble note. 90

The prime actuator is constantly driven by means of any suitable motor which may be situated in any convenient position and which is shown conventionally at 27, through convenient transmitting devices, shown as a 100 pulley 28 on the motor shaft, geared by a belt 29 with a pulley 30 combined with the prime actuator.

The shoes are connected to the action of the instrument, for instance, to the wippens 105 6 which operate the hammers 5, by flexible connections, such as tapes 31. The tapes may be attached to the shoes and wippens conveniently by means of clips 32. This mode of connecting the tapes to the wippens 110 is desirable in that the connection may be made without in any wise altering the wippens. When the shoes 24 are made to contact with the constantly-rotating prime actuator, they are caused to oscillate, pull upon 115 the appropriate tapes 30, and operate the corresponding hammers, in the illustrated example of the invention through the medium of the wippens 6.

As before described, the carrier 8 is so 120 arranged that it may be shifted by a forwardly or outwardly falling movement from its operative position to afford ready access to the string-plate of the instrument, without disconnecting any element of the player 125 mechanism or the connection thereof with the action of the instrument. This is accomplished by pivoting the carrier below its longitudinal median line. The degree of falling movement of the carrier is increased 130

to provide greater facility of access to the string plate by extending the legs 9 considerably below the player mechanism supported by the body-portion of the carrier 5 and pivoting the ends of the legs to the case. The carrier so pivoted, and all the mechanism supported thereby may be swung away from in front of the string plate, and downward or in a general direction toward 10 the piano keys. This operation is permitted by reason of the flexible character of the connections 31, and is of great advantage for the reasons hereinbefore stated.

In prior arrangements of the general type indicated when it became necessary for any reason to move the carrier and the mechanism supported thereby for the purpose of getting at the strings of the instrument, it was essential also to disconnect the connections between the shoes and the action. This is a tedious and time-consuming operation involving as it does the act of disconnecting each of the several connecting mediums and the subsequent connection thereof to make 20 the player mechanism again operative. According to my invention, the player mechanism may be shifted out of the way to afford access to the strings of the instrument without disconnection of any part thereof with 25 the action of the instrument. I contemplate also, the incorporation with the carrier, so as to partake of the movements thereof, of expression mechanism whereby any string of the instrument may be caused to strike as 30 softly or loudly as desired within the capacity of the instrument. It is desirable and of advantage that this expression mechanism may be controlled by finger keys located at the front of the instrument within easy 35 reach of the operator. To this end a flexible bar 33, preferably consisting of a plurality of sections, is arranged to operate against the hammers to position them at a greater or lesser distance from the strings of the instrument. The tone produced by the hammers depends upon the length of stroke of the hammers, being softer when the hammer has a minimum stroke and increasing in volume according to the increase of length 40 of the hammer stroke. The flexible bar may be manipulated so as to bring either of its ends or its central portion, and the hammers associated therewith, to or away from the strings for the purpose of securing desired 45 expression. The manipulation is accomplished by mounting the bar at and intermediate its ends in crank arms 34, 35, 36, from shafts 37, 38, 39, journaled in bearings 40 with which the carrier 8 is provided, where- 50 by when one or more or all of said shafts are rotated, the corresponding part or parts, or the entire bar may be moved to or away from the strings. The shafts are rocked by means of rods 41 severally appropriated 55 thereto and connected to crank arms 42 with

which the shafts are provided, which rods are attached at their lower ends to expression-levers 43 pivoted to brackets 44 secured beneath the key-board of the instrument, which expression-levers and the rods connected thereto may be normally held in predetermined position, such for instance, as to impart pianissimo expression, by means of springs 45 connected to said levers and the brackets 44. As the expression-levers 70 exert a direct action upon the crank arms to rock the shafts, the rods are necessarily rigid in operation. In order to permit the carrier and its contained mechanism, including the expression bar, to be swung downward and 75 away from the piano strings as above described, I interpose a hinge 46 in each rod, and provide sleeves to cover the hinges. When the sleeves are adjusted to uncover 80 the hinges the rods may move about the latter to admit of the described shifting of the carrier, and when covered by the sleeves the rods are made rigid for rocking the shafts 34, 35, 36. Stops 47 are provided on the rods adjacent the hinges to support the 85 sleeves when in position to cover the hinges.

It is of great advantage that the expression levers 43 be capable of free manipulation manually at the will of the operator, during the playing of a musical composition 90 to accentuate or modulate different notes or passages, and also that said levers may be set in any desired position to produce desired expression, and maintained in that position, as for example, when the operator 100 does not care to manipulate the levers, or when it is desired to permit the player mechanism to operate entirely automatically, as for dance music at small gatherings where all the guests desire to participate in the 105 dance. I accomplish this by combining with the free ends of the levers a rack 48 having slots or passages 49 in which the levers move. One wall of each slot is provided with a series of rests consisting of teeth 50 with 110 intervening spaces, and in the preferred and illustrated arrangement, the levers are provided with catches 51 provided thereto at one side thereof and normally moving in front of the rests, so that the free manual 115 manipulation of the levers is not interfered with. When it is desired to set the levers to obtain desired expression, the ends 52 of the catches are moved, rocking the catches and throwing the ends 53 thereof into engagement with any desired rest 50. When so in engagement with the rests the catches hold the levers in set position. It is obvious that the lever controlling the bass note expression may be set to piano, that controlling 120 the middle notes to forte and the treble note lever to fortissimo; or that other variation of set expression may be secured. The catches shown are arranged to automatically release themselves upon depression of the 125 130

levers, the increased gravity of the ends 52 operating to swing the ends 53 out of engagement with the rests 50. The action of gravity for this purpose may be assisted or 5 replaced by springs 54. In the embodiment of the arrangement shown the catches, when made to engage the rests, remain in such engagement until the levers are depressed, because of the action of the springs 45, which, 10 by their action on the levers 43, hold the ends 53 of the catches against the teeth 50 and prevent the ends 52 from releasing the engagement until the levers are depressed.

I contemplate driving the music sheet 15 take-up roll of the music roll holder directly from the prime actuator, materially simplifying the arrangement. As such music roll holders are known I do not illustrate in detail, but show only conventionally one end of 20 a shaft 55 involved in driving the latter. For the purpose stated a flexible shaft 56, connected to the shaft for driving the same, is coupled to the prime actuator 25 and imparts rotation therefrom to the said shaft 55. 25 The flexibility of the shaft permits of the shifting of the prime actuator 25 together with the carrier and also the shifting of shaft 55, as may be desired in regulating the speed of rotation of the take-up roll.

30 Having thus described my invention, what I claim as new and desire to secure by Letters Patent is:

1. The combination with an upright piano the action of which is in the upper part 35 of the casing, of piano-playing mechanism located in the upper part of the casing, means for connecting said mechanism with the action of the instrument, a carrier supporting said playing mechanism and movable from in front of the strings of the piano 40 without disconnection of the playing mechanism from the action.

2. The combination with a piano in which a member of the string-plate and action are 45 located in the upper part of the casing, of a player-mechanism carrier, means for movably supporting said carrier within the piano casing whereby it may be moved toward and from the string-plate, playing mechanism supported by the carrier, and means connecting said mechanism with the piano 50 action.

3. The combination with an upright piano having an action located in the upper part 55 of the casing thereof, of player-mechanism arranged in the upper part of the casing, flexible means connecting said mechanism with the action, and a carrier supporting said mechanism shiftable from in front of 60 the string-plate of the instrument without disconnecting the player-mechanism from the action.

4. The combination with an upright piano having an action located in the upper part 65 of the casing, of player mechanism located

in the upper part of the casing of the instrument, means connecting said mechanism with the action, and a carrier supported by said player mechanism, said carrier pivoted to swing away from the string-plate of the 70 instrument and in the direction toward the keyboard whereby access may be had to the strings of the instrument without disconnecting the player-mechanism from the action.

5. The combination with an upright piano having an action located in the upper part of the casing, of player-mechanism arranged in the upper part of the casing, means connecting said mechanism with the action, and 80 a carrier supporting said player mechanism and pivoted to swing away from the string-plate of the instrument and in the direction toward the keyboard, whereby access may be had to the strings of the instrument without disconnecting the player mechanism from the action, and means for maintaining said carrier and player mechanism in operative 85 position with relation to the action.

6. The combination with an upright piano 90 having an action located in the upper part of the casing thereof, of a carrier pivotally connected in the upper part of the casing, player mechanism supported by said carrier, flexible means connecting said player mechanism to the action, and means for pivoting said carrier at a point below the player mechanism supported thereby, whereby said carrier and the player mechanism may be swung away from the strings of the piano 100 and in the direction toward the keyboard, without disconnecting the player mechanism from the action.

7. The combination with an upright piano having an action located in the upper part 105 of the casing, of a carrier arranged in the upper part of the casing, and means for pivoting the carrier to swing on an axis located below the longitudinal median line of the carrier, player mechanism supported by said 110 carrier, and means for connecting said mechanism with the action.

8. The combination with an upright piano having an action located in the upper part 115 of the casing, of a carrier arranged in the upper part of the casing, means for pivoting the carrier to swing on an axis located below the longitudinal median line of the carrier, player-mechanism supported by said carrier, and flexible means for connecting 120 said mechanism with the action.

9. The combination with an upright piano having an action located in the upper part 125 of the casing, of a carrier arranged in the upper part of the casing, means for pivoting the carrier to swing on an axis located below the longitudinal median line of the carrier, player-mechanism supported by said carrier, means for connecting said mechanism with the action, and releasable means for main- 130

taining said carrier and the mechanism supported thereby in operative position.

10. The combination with an upright piano having an action located in the upper part of the casing, of a carrier arranged in the upper part of the casing, means for pivoting the carrier to swing on an axis located below the longitudinal median line of the carrier, player-mechanism supported by said carrier, flexible means for connecting said mechanism with the action, and releasable means for maintaining said carrier and the mechanism supported thereby in operative position.

15. 11. The combination with an upright piano having the action located in the upper part of the casing thereof, of a carrier located in the casing above the action and pivoted beneath its longitudinal median line, player mechanism supported by said carrier, and means connecting said mechanism with the action.

20. 12. The combination with an upright piano having an action located in the upper part of the casing thereof, of a carrier in the upper part of the casing having depending legs pivoted at their lower ends, player mechanism supported by said carrier, and means connecting said mechanism with the action.

25. 13. The combination with an upright piano having an action located in the upper part of the casing thereof, of a carrier in the upper part of the casing having depending legs pivoted at their lower ends, player mechanism supported by said carrier, means connecting said mechanism with the action, and means for maintaining the carrier and player mechanism in operative position.

30. 40. 14. The combination with an upright piano having an action located in the upper part of the casing thereof, of a carrier, player-mechanism supported by said carrier, means for connecting said mechanism to the action, said carrier being shiftable away from the string-plate of the instrument, and in the direction toward the keyboard, an expression device supported by said carrier, expression-levers, rods intermediate said levers and expression device, and hinges in said rods.

35. 45. 55. 60. 15. The combination with an upright piano having an action located in the upper part of the casing thereof, of a carrier, player-mechanism supported by said carrier, means for connecting said mechanism to the action, said carrier being shiftable away from the string-plate of the instrument and in the direction toward the keyboard, an expression device supported by said carrier, expression-levers, rods intermediate said levers and expression device, hinges in said rods, and means combined with said hinges whereby the rods may be maintained rigid.

65. 16. The combination with an upright

piano having an action located in the upper part of the casing thereof, of a carrier, player-mechanism supported by said carrier, means for connecting said mechanism to the action, said carrier being shiftable away 70 from the string-plate of the instrument and in the direction toward the keyboard, an expression device supported by said carrier, expression-levers, rods intermediate said levers and expression device, hinges in said rods, and sleeves combined with said hinges 75 for the purpose set forth.

17. The combination with an upright piano, the action of which is in the upper part of the casing thereof, of piano playing 80 mechanism including a prime actuator located in the upper part of the piano casing, means for connecting said mechanism with the action of the instrument, a music sheet take-up roll, and a flexible shaft deriving 85 movement from the prime actuator for operating the said take-up roll.

18. The combination with an upright piano the action of which is in the upper part of the casing thereof, of piano-playing 90 mechanism, including a prime actuator located in the upper part of the casing, means for connecting said mechanism with the action of the instrument, a music sheet take-up roll, means deriving movement from said 95 prime actuator for operating the said take-up roll, and a carrier supporting said playing mechanism movable from in front of the strings of the piano without disconnecting the playing mechanism from the action, 100 or the driving means for the said take-up roll.

19. The combination with an upright piano, the action of which is in the upper part of the casing thereof, of piano playing 105 mechanism including a prime actuator located in the upper part of the casing, means for connecting said mechanism with the action of the instrument, a music sheet take-up roll, a flexible shaft deriving movement 110 from the prime actuator for operating the said take-up roll, and a carrier supporting said playing mechanism movable from in front of the strings of the piano without disconnecting the playing mechanism from 115 the action nor the driving means for the said take-up roll.

20. The combination with an upright piano having an action located in the upper part of the casing thereof, of a carrier, 120 player mechanism supported by said carrier, means for connecting said mechanism to the action, said carrier being arranged to be shifted away from the string-plate of the piano and toward the keyboard, an expression device supported by said carrier, operating levers therefor, and operative connections between said levers and expression device.

21. The combination with an upright- 130

- piano the action of which is in the upper part of the casing, of piano-playing mechanism located in the upper part of the casing, means connecting said mechanism with the action of the instrument, a pair of swinging brackets pivotally connected within the piano casing, and a carrier for the playing mechanism supported at its opposite ends upon said brackets, the construction and arrangement of parts being such that the carrier and playing mechanism may be moved from in front of the strings of the piano without disconnection of the playing mechanism from action.
- 15 22. The combination with an upright piano the action of which is in the upper

part of the casing, of piano-playing mechanism located in the upper part of the casing, means connecting said mechanism with the action of the piano, a carrier supporting said playing mechanism, comprising a body 8, having legs 9, at its opposite ends and means for pivotally mounting the carrier within the piano casing.

In testimony whereof I have hereunto set 25 my hand in presence of two subscribing witnesses.

IRVING B. SMITH.
